DESIGN FOR A FOOD WARMER

Theodore Ulmer, Burbank, Calif., assignor to Mars
Engineering & Mfg. Co., Burbank, Calif., a cor-
poration of California

Application June 10, 1948, Serial No. 146,887

Term of patent 14 years

(Cl. D44—1)

To all whom it may concern:

Be it known that I, Theodore Ulmer, a citizen of the United States of America, residing in the city of Burbank, in the county of Los Angeles, State of California, have invented a new, original, and ornamental Design for Food Warmer, of which the following is a specification, reference being had to the accompanying drawing, forming a part thereof.

Figure 1 is an exploded perspective view, in elevation, of a food warmer, showing my design; and Figure 2 is a top plan view thereof.

I claim:

The ornamental design for a food warmer, substantially as shown.

THEODORE ULMER.
